UNITED STATES PATENT OFFICE.

JOHN J. TATUM, OF BALTIMORE, MARYLAND, ASSIGNOR, BY MESNE ASSIGNMENTS,
TO P. H. MURPHY COMPANY, OF PARNASSUS, PENNSYLVANIA, A CORPORATION
OF PENNSYLVANIA.

CAR-ROOF.

1,087,408.

Specification of Letters Patent. Patented Feb. 17, 1914.

Application filed May 22, 1912. Serial No. 698,957.

To all whom it may concern:

Be it known that I, JOHN J. TATUM, a citizen of the United States, residing at Baltimore, in the State of Maryland, have 5 invented certain new and useful Improvements in Car-Roofs, of which the following is a specification.

It is a well known fact that car roof sheets must be secured to the car in such manner 10 that they are free to move relatively to each other and longitudinally as well as transversely of the car to compensate for the various movements of the car when in transit known as "weaving" and "jacking up" 15 of the cars in making repairs to the trucks, wheels, etc. If the sheets are not movable relatively to each other and movable longitudinally of the car, they will tear along 20 the eaves of the car and the seams formed along their side marginal edges will open, thus causing the roof to leak.

The object of my invention is to construct a roof, the individual sheets of which are mounted of the sub-structure and movable 25 transversely and longitudinally thereof, and whose side margins are interlocked to form seams and whose edges are loosely secured to a flashing on top of the car while an intermediate portion of the sheets 30 overhangs the flashing and constitutes a covering for the nails which secure the flashing to the sides of the car, the sheet having a half roll at the eaves to take up the transverse movements of the sheets and prevent 35 the edge of the flashing cutting into the roof sheet and the edge of the roof sheet cutting the flashing; and with these and minor objects in view my invention consists of the parts and combination of parts as will be 40 fully pointed out.

In the drawing, Figure 1 is a perspective view of a car broken away, embodying my invention; Fig. 2 is an enlarged detail sectional view; Fig. 3 is an enlarged perspective view of my improved sheet, broken away, and Fig. 4 is a transverse sectional view through two interlocked adjacent roof sheets.

The reference numeral 1 designates the 50 side plate of a car, 2 the side post, 3 the carline and 4 the side sheathing. The sub-structure, or wooden roof sheathing 5, terminates along a line short of the eaves of the car as shown, thereby forming a rabbet back 55 from the eaves of the car. The flashing is of

the type shown in my Patent No. 1,005,757, the salient feature of which is the thickened base which prevents damage to the flashing and roof sheets from "cornering" and "side wiping." The top of the flashing is 60 flush with the bottom of the rabbet. The flashing 7 is nailed to the upper portion of the fascia 6, and bent over the eaves of the car terminating in an upward rebend 8 lying in the rabbet as clearly shown in the drawings. 65

One side margin or edge of the roof sheet 9 is rebent to form a side wall 10 and an inwardly extending overhang 11 disposed over the main body of the sheet, while the other 70 side margin or edge of the sheet is bent upwardly to form a wall 12 and thence outwardly from the sheet as at 13 and terminating in an under rebend 14 spaced therefrom. The wall 12 is higher than the wall 75 10 on the same sheet, so that when two roofing sheets are brought together the wall 10 and overhang 11 of one sheet may be fitted loosely under the portion 13 and within the rebend 14 of the adjacent sheet; the portion 80 13 serving as a covering for the joint between the two sheets, while the rebend 14 acts as a housing for the overhang 11 of the adjacent sheet, thus completely closing the joint between the sheets against the passage 85 of water, snow, etc. The relative heights of the walls 11 and 12 are such that the overhang 11 is spaced from the rebend and the portion 13, thus preventing moisture from "creeping" up the wall 10 and along the overhang 90 11, thence into the joint between the sheets inasmuch as the edge of the overhang acts as a "drip" by reason of its being spaced from the rebend 14 and portion 13, whereby the moisture will drip from the edge of the 95 overhang, thence onto the rebend which sheds it on the main body of the roof sheet owing to its slight downward deflection.

From the above, it will be seen that I interlock the side marginal edges of the roof sheets to form a seam which will permit of the sheets moving relatively transversely. The roofing sheet is formed with a roll 15 at the eaves, then closely rebent at 16, and then bent to lie in the rabbet under the 100 main body of the sheet as at 17 to lie within the rebend 8 of the flashing with which it forms a loose joint for the roof sheet on top of the car, which is efficiently protected from the elements. The closely rebent por. 110

tion 16 of the roof sheets overlies the nails of the flashing and prevents them from working out and at the same time protects them from the elements, thus eliminating corrosion between the nail heads and the flashing. The roll 15 formed in the roof sheets at the eaves of the car acts more or less as a shock absorber for the sheets and permits them to move transversely of the car without imposing any strain on the sheet or flashing, as all strains taken up by the roll are directed through the close rebend 16 against the side of the car. The roll also eliminates the liability of the roof sheets tearing along the eaves of the car. As stated, the seam between the roof sheets and the flashing permits the roof sheets to move longitudinally of the car. The construction of the joint between the flashing and the roof sheets is such that it is practically impossible for rain, snow, etc., to enter it.

What I claim and desire to secure by Letters Patent is:—

- 25 1. A car roof sheet having a roll at its eaves end below the plane of the sheet, a close rebent portion depending from said roll and an end portion extending from the rebent portion under and spaced from the main body of the sheet.

- 30 2. A car roof comprising movably secured

metal sheets mounted on the sub-structure and movable transversely thereof and whose side margins are interlocked to form seams, and whose main body is bent to form a roll, 35 and a close rebend, intermediate its ends, the outer ends of the sheet being bent on top of the sub-structure, and a flashing forming a loose joint with the outer edges of the sheets.

3. A car roof comprising movably secured metal sheets mounted on the sub-structure and movable transversely thereof, and whose side marginal edges are interlocked to form seams, and whose main body is bent to form 45 a roll at the eaves of the car, and a close rebend depending from said roll below the eaves of the car, intermediate its ends, the outer ends of the sheets being bent on top of the car, and a flashing secured to the side 50 of the car and terminating in an upward open rebend on top of the car to form a loose joint with the outer edge of the roof sheets; the close rebend of the sheets overlying the nails which secure the flashing to the sides of the car.

In testimony whereof I affix my signature in presence of two witnesses.

JOHN J. TATUM.
